LIFE PRESERVER

Filed March 2, 1931

UNITED STATES PATENT OFFICE

GUSTAF MATTSON, OF PORTLAND, OREGON

LIFE PRESERVER

Application filed March 2, 1931. Serial No. 519,424.

My invention is primarily adapted for the use of swimmers and for use in aquatic sports. It having its greatest value for use by those who are engaged in the primary stages of 5 learning to swim.

The device is comprised of an impervious member adapted for being worn and fitted to the body of the user and preferably beneath, or between the body of the wearer, 10 and the bathing suit. The device being preferably made from impervious material, light in weight and compartmented, to give greater safety to the device and to cut down the weight. Each compartment having separate 15 mouth pieces and valves for inflating and deflating purposes.

The device is comprised of half sections adapted to fit about the waist of the user and between the arms and the hips and for 20 being laced, or otherwise secured, in place upon the body of the wearer.

The object of my device is to provide a safe buoyant member to be worn by swimmers and to add zest and safety to the swim- 25 mer and to permit the wearer to swim with less effort and greatest safety.

A still further object of my device is to pro- 30 vide a life preserver that may be easily placed upon the body of the user and which will per- mit the user to develop the desired amount 35 of buoyancy to be furnished by the life pre- server.

A further object of my device consists in 35 providing a life preserver, through the use of which, the amateur swimmer may be pro- 40 vided with a safety device that will not inter- fere with his learning to swim, that will be comfortable while being worn, and through the use of which, the desired amount 45 of buoyancy may be developed by the user, as, and when required.

A further object of my invention consists 50 in providing a device that may be formed integral with a bathing suit.

A still further object of my invention con- 55 sists in providing a life preserver comprised of inner and outer walls, each of which may be made of rubber, or rubberized material with the inner wall being made heavier than 60 the outer wall so that any compression that

may occur, due to the inflating of the same, will be reflected in the outer, thinner mate- 55 rial, to thereby prevent undue compression being made upon the body of the wearer and to cause an apparent lesser diameter of the device itself.

With these and incidental objects in view, the invention consists in certain novel fea- 60 tures of construction and combination of parts, the essential elements of which are set forth in the appended claim, and a preferred form of embodiment of which is hereinafter shown with reference to the drawings which accompany and form a part of this specifica- 65 tion.

In the drawings;

Fig. 1 is a front view, partially in section, 70 of one of my devices shown in use upon the body of a female wearer.

Fig. 2 is a perspective, side view partially 75 in section, of the device shown removed from the wearer.

Fig. 3 is a fragmentary, top, plan view, of the assembled device.

Fig. 4 is a fragmentary, sectional, side 75 view of the assembled device, shown re- moved from the wearer.

Fig. 5 is a fragmentary, sectional, end view 80 of the device, the same being taken on line 5-5 of Fig. 4, looking in the direction in- dicated.

In Figs. 3 and 4 I have shown the device 85 as being comprised of inner and outer skin members with the inner skin member 9 being made of heavier material, so that when the body of the device is inflated, the inflation will be reflected in the outer skin member to thereby, in a measure, relieve undue pres- 90 sure being made to engage the body of the wearer.

In Fig. 1 I have shown a device that may be woven integral with the bathing suit it- 95 self; when so formed integral with the bath- ing suit the life preserver portion of the bathing suit will be maintained in desired position when placed about the body of the wearer.

My device is adapted for use of the amateur swimmer primarily, but may be used with 100

comfort and facility by any one engaged in aquatic sports.

The device is comprised of a girdle member composed of two, or more sections adapted for being secured, or hinged together upon their meeting edges, the girdle being divided into compartments to insure safety and comfort to the wearer; means being provided for inflating and deflating each section independently of the other by the wearer while the same is in actual use upon the body of the wearer and while the wearer and the device are actually immersed, or partially immersed.

Like reference characters refer to like parts throughout the several views.

I form my device primarily of an inner skin 1 and an outer skin 2, secured together at their meeting edges, as by a zipper, as illustrated at 3.

I do not wish to be limited to any specific form of fastening for securing the girdle together, as any form of fastening may be used. If material of sufficient flexibility is used, the device may be placed upon the body of the wearer as an endless compartmented girdle member.

I preferably secure the inner and outer skins together at one, or more points as illustrated at 4 as by vulcanizing, or cementing.

To comprise the girdle into compartments, this fastening to form compartments, is done as a precautionary measure and to insure buoyancy, sufficient to maintain the wearer's body afloat. In the event of one of the compartments becoming punctured from any cause the added compartments continue to function.

Tubes 5 and 6 here shown as two in number communicate with each of the compartments of the girdle, with mouth pieces and valves 7 and 8 secured to their ends, in order that the wearer may inflate each compartment to the desired amount to create a buoyancy sufficient for the purpose and object of the wearer. Each of the mouth pieces is comprised of a mouth piece and a valve in order to maintain the exhaled air within the desired compartment at the pressure secured.

If he desires to inflate the girdle to insure complete buoyancy of the body of the wearer a larger pressure is disposed within the girdle to inflate the same to a larger extent than if a lesser buoyancy is required.

The inner and outer skin members are secured together at their peripheral edges at 9, by vulcanizing, or by any other means.

My device may be worn without being covered, or protected but I recommend the use of the same as being worn between the body of the wearer and the bathing suit 10, and when so worn, its presence will not be apparent, unless the same is unduly inflated.

Where a relatively close fitting knitted bathing suit is to be worn as an outer covering for the life preserver as herein outlined,

the same may be comprised of lighter weight material which will insure greater comfort to the wearer.

While the form of mechanism herein shown and described is admirably adapted to fulfill the objects primarily stated, it is not intended to confine the invention to the one form of embodiment herein shown and described, as it is susceptible of embodiment in various forms, all coming within the scope of the claim which follows.

What I claim is:

A life preserving suit adapted to be worn about the waist over the wearer, independent air tight compartments between the arms and hips of the wearer, said compartments comprising primarily of inner and outer skin members of flexible material, the outer skin member being made of lighter material, and valve operated inflating tubes connected to each of the compartments.
